RAZOR STROP COMPOUND

Louis Diehl, Sharpsburg, Pa.

No Drawing. Application May 25, 1955,
Serial No. 511,120

1 Claim. (Cl. 106—36)

This invention relates to a liquid composition for cleansing and dressing razor strops or hones and it is among the objects thereof to provide a composition including a friction agent for rapidly bringing up the edge of a razor.

It is well known that extremely fine steel cutting edges consist of microscopic teeth or serrations which individually bend or are displaced in the normal use as in a razor, and it requires frequent stropping to reline these microscopic teeth to form a smooth cutting edge. Various kinds of razor strop dressing, including soaps, waxes or oils, have been employed to provide a surface on the strop to thereby hasten the alignment of the cutting edge. These materials are unsatisfactory for one reason or another; for example, they may provide a dragging feel to the strop but by their very nature act as a lubricant instead of a friction agent and thereby defeat the purpose of the strop.

In accordance with the present invention, I employ a composition preferably in liquid form, which acts to cleanse and protect a strop from the accumulation of objectionable substances which may, for example, cling to the plate of the razor and which are imparted to the stropping surface through normal use. This same composition at the same time provides an ideal surface on

2

the strop for more positive and quicker aligning of cutting edges, whether serrated or perfectly smooth.

I have found by experimentation that a composition suitable for the purpose is sodium benzoate in powder form when held in suspension by a solution of gum arabic.

I have found that by compounding one part by volume of gum arabic solution made by mixing one part gum arabic powder with approximately 5 parts by volume 10 of water and 1 part by volume sodium benzoate powder and perhaps coloring, a desirable composition is produced for cleansing and dressing a razor strop and when so used, it will speedily bring up the edge of the razor in a manner that it will hold up for a surprisingly 15 longer period of time than were such composition not employed. The solution or composition may be applied either to leather, canvas or other suitable stropping material. It may also be used on other than conventional strops such as mechanical devices, rotary drums, etc.

20 While sodium benzoate may be compounded with other solutions, I have found gum arabic the most satisfactory as the sodium will not settle out or powder up on the strop.

25 Although one embodiment of the invention has been herein illustrated and described, it will be evident to those skilled in the art that various modifications may be made in the proportions and compounding of the ingredients without departing from the principles herein set forth.

30 I claim:

The composition for dressing razor strops consisting of one part by volume of sodium benzoate powder suspended in one part by volume of gum arabic solution consisting of one part gum arabic powder and substantially five parts 35 by volume of water.
